UNITED STATES PATENT OFFICE.

LLOYD ROVELL, OF HARRIETTE, MICHIGAN.

ENVELOP.

1,110,964.

Specification of Letters Patent. Patented Sept. 15, 1914.

Application filed December 19, 1910. Serial No. 597,997.

To all whom it may concern:

Be it known that I, LLOYD ROVELL, a citizen of the United States of America, residing at Harriette, in the county of Wexford 5 and State of Michigan, have invented new and useful Improvements in Envelops, of which the following is a specification.

This invention relates to envelops, and it has for an object to provide an improved 10 construction of envelop wherein efficient means are employed to prevent the unsealing thereof by steaming or like operations.

In the drawing, forming a portion of this specification and in which like numerals of 15 reference indicate similar parts in the several views—Figure 1 is a plan view of the blank. Fig. 2 is a perspective view of a portion of the sealing tongue showing the manner of folding the seal-forming element 20 thereon. Fig. 3 is a similar view illustrating another position of the parts in the folding of the said sealing element. Fig. 4 is a plan view of a portion of the envelop showing the locking flap folded. Fig. 5 is a partial transverse section through the closed envelop.

The envelop is constructed from a blank 1 which includes the usual front wall 2, the 5 end flaps 3 and 4, the bottom flap 5 and the sealing flap 6. Near one end of the flap 3 is cut a longitudinal slot 7 which registers 10 with a similar slot 8 in the flap 4 when the flaps 3 and 4 are folded over each other. An adhesive substance 9 is applied to the 15 flap 3 at one side thereof and entirely surrounds the slot 7. A similar substance 10 is applied to one side of the flap 4 to entirely surround the slot 8 therein.

The sealing flap 6 carries a substantially 20 triangular extension 11 which is folded on itself on the longitudinal line 12, then on the line 15 and then on the transverse lines 13. From the illustration shown in Figs. 2 and 3, it will be seen that when the extension 25 is folded as described, it is provided with terminal pockets 14. The terminals of the extension may be interlocked with each other by inserting the corner of one terminal in the pocket 14 in the opposite terminal of 30 the extension, as illustrated. From the con-

struction it will be readily understood that a novel form of sealing element 14' is constructed.

In practice, the end flaps of the envelop are folded to lie on each other so as to cause 55 the slots therein to register. The bottom flap is folded to overlie one of the end flaps and in a manner to cause the longitudinal slot 15' therein to coincide with the slots in the end flaps. It will of course be understood that before folding the flaps as above specified, the adhesive substance on each flap will be moistened so as to cause the flaps to adhere to each other when they are properly folded. When the end flaps and the bottom 60 flap are folded, the sealing flap 6 may be folded to its closed position and the tongue thereof may be inserted through alining slots 7, 8 and 15'. The folded portions of the tongue engage the edges of the slots. 70 Should an attempt be made to withdraw the tongue, the sealing tongue would probably be torn from the body of the flap, indicating that such an attempt had been made.

I claim:

An envelop having overlapped flaps provided with alined slots, a sealing flap, and a triangular extension carried by the sealing flap and folded on itself in a longitudinal direction and immediately at the middle of 80 said extension, the extension having intermediate transverse weakened lines and outer transverse weakened lines, the said extension being folded on itself from said transverse lines whereby the folded portions define pockets at the ends of the extension, the pocket forming portions being disposed relatively so that the pocket at one end receives the opposite pocket end of the extension, the distance between the intermediate weakened 90 lines being equal to the length of the slots so that the extension in its folded condition may be extended through said slots, as and for the purpose specified.

In testimony whereof I affix my signature 95 in presence of two witnesses.

LLOYD ROVELL.
